UNITED STATES PATENT OFFICE.

RUSSEL G. WOODWARD, OF WAUKEGAN, ILLINOIS, ASSIGNOR TO UNION SPECIAL MACHINE COMPANY, OF CHICAGO, ILLINOIS, A CORPORATION OF ILLINOIS.

FEEDING MECHANISM FOR SEWING-MACHINES.

1,211,804.

Specification of Letters Patent. Patented Jan. 9, 1917.

Application filed June 17, 1910. Serial No. 567,518.

To all whom it may concern:

Be it known that I, RUSSEL G. WOODWARD, a citizen of the United States, residing at Waukegan, in the county of Lake, State of Illinois, have invented certain new and useful Improvements in Feeding Mechanisms for Sewing-Machines, of which the following is a description, reference being had to the accompanying drawing and to the letters and figures of reference marked thereon.

The invention relates to new and useful improvements in feeding mechanisms for sewing machines, and more especially to a feeding mechanism embodying two feed dogs which are given a differential movement relative to each other.

An object of the invention is to provide a mechanism for operating the two feed dogs wherein said feed dogs will be positively moved back and forth and up and down, with as little wear as possible, and with a minimum amount of vibration in the parts being operated.

A further object of the invention is to provide a feeding mechanism of the above character with two feed bars which are joined together so that said bars may move in unison to carry the feed dogs into engagement with the fabric and so that one of the feed bars may move longitudinally relative to the other for imparting a differential feeding movement to one of the feed dogs.

These and other objects will in part be obvious, and will in part be hereinafter more fully described.

In the drawings which show by way of illustration one embodiment of the invention: Figure 1 is a front view of a portion of a machine having my feeding mechanism applied thereto. Fig. 2 is an end view of the same. Fig. 3 is a plan view of the feeding mechanism. Fig. 4 is a perspective view of the essential parts of the feeding mechanism. Fig. 5 is a detail showing the sliding connection between the two feed bars. Fig. 6 is a detail in side elevation of the main feed bar and the support for the feed dog.

My improved feeding mechanism comprises two feed dogs which are preferably arranged one directly in advance of the other, which feed dogs are also preferably operated in a manner to cause a slightly faster feeding movement by the forward feed dog than by the rearward feed dog whereby the fabric being stitched may be

crowded underneath the presser foot to the stitching mechanism, so that all liability of stretching the fabric and operating upon loose knit goods, is avoided.

My invention is especially adapted for an overseaming machine wherein knit goods may be trimmed and the edge of the fabric or fabrics being joined covered with overseaming stitches.

In the drawings I have shown a portion of an ordinary sewing machine which consists of a bed plate 1 on which is mounted an overhanging arm carrying a needle vibrating lever which reciprocates in the ordinary way, a needle 2. The work being operated upon is supported by the usual cloth plate held in cooperative relation with the feeding mechanism by the presser foot, which may be of any desired construction.

My improved feeding mechanism consists of a main feed dog 3, and an auxiliary feed dog 4. As clearly shown in the drawings, the auxiliary feed dog is mounted so as to engage the fabric directly in front of the main feed dog. The main feed dog 3 is connected to a main feed bar 5, at the forward end thereof. As clearly shown in the drawings the main feed dog is carried directly by a supporting arm 6, which is adjustably connected to a supporting block 7. The block 7 is provided with a rib 8, which engages a recess in the lower face of the supporting arm 6. The arm 6 is formed with slots 8' and screws 9 extending through the slots and engaging the block 7 to hold the arm in its various adjusted positions on the block 7. It will readily be seen by loosening the screws 9, that the main feed dog may be adjusted transversely of the main feed bar. The block 7 supporting the main feed dog is carried by a shank 10 which is adjustably connected to the main feed bar by means of a screw 11 which passes through a vertical slot in said shank and is threaded into the main feed bar. This slotted connection for the shank of the supporting block carrying the main feed dog, allows for a slight vertical adjustment of the feed dog relative to the feed bar on which it is mounted.

The auxiliary feed dog 4 is carried by an auxiliary feed bar 12. Said auxiliary feed bar at the forward end carries an upwardly and forwardly projecting arm 13 on which the feed dog 4 is mounted. Said arm 13 is cut away underneath so as to allow clearance

for the operation of the looper. Inasmuch as the feed dog carried by said auxiliary feed bar is in advance of the main feed dog and the stitching point, this clearance for 5 the looper in the auxiliary feed bar is essential. The forward end of the arm 13 is provided with a rib 14, which engages a recess formed in the rear face of the shank supporting the auxiliary feed dog 4. Said 10 shank is also slotted vertically and a screw 15 passing through the slot into the end of the arm 13 will secure the auxiliary feed dog on the end of the supporting arm therefor. By loosening the screw 15, said auxiliary 15 feed dog may be adjusted vertically relative to the auxiliary feed bar.

As a means for operating the feed bars to give the feed dogs their various feeding movements, I have provided the usual feed 20 rocker 16, which is pivoted at 17' to ears carried by the bed plate 1. Said feed rocker 16 has rigidly secured thereto an arm 17, which extends forwardly to a point substantially over the main shaft 18. An eccentric 19 25 carried by the main shaft 18 coöperates with a strap 20 which at its upper end is pivoted to the arm 17 carried by the rocker frame. As the main shaft rotates, the eccentric through its connection with the arm 17 will 30 oscillate the feed rocker back and forth. The main feed bar 5 at its rear end is pivotally connected to the feed rocker so that the oscillating movements of the feed rocker are directly imparted to the main feed bar 35 moving the same back and forth to feed the fabric in the well known way.

The auxiliary feed bar 12 is slidingly connected to the main feed bar. Said main feed bar has rigidly attached thereto on its under 40 face, a hardened plate 21 which extends laterally from the main feed bar and on this hardened plate the auxiliary feed bar rests and slides. The auxiliary feed bar at its rear end carries a downwardly projecting arm 22, which has a laterally projecting lug 23 that is adapted to engage the under surface of the main feed bar or a wear plate moving therewith. This lug carried by the arm projecting from the auxiliary feed bar 45 will prevent the rear end of the feed bar from being raised but tilted longitudinally as the auxiliary feed dog is pressed up against the fabric into feeding engagement therewith. To further guide the auxiliary 50 bar, I have provided a plate 24 which is rigidly secured to the upper face of the main feed bar by screws 25. Said plate 24 projects laterally from the main feed bar; over the auxiliary feed bar, and at its outer end 55 carries a downwardly projecting lip 26 which extends down across the face of the auxiliary feed bar.

From the above description it will be noted that I have formed a box or bearing 60 by the hardened plate 21 and the plate 24

with the depending lip 26 together with the side face of the main feed bar and in this box or bearing the auxiliary feed bar slides back and forth when a differential movement is given to said auxiliary feed dog. 70

The rear end of the auxiliary feed bar carries upwardly spaced ears 27. A link 28 is pivoted between the ears 27 at one end and at the other end is pivotally connected with a stud 29 adjustably mounted in a slot 30 75 formed in an upwardly projecting arm 31 carried by the feed rocker 16. A nut 32 on the outer end of the stud 29 will hold said stud in its adjusted positions.

The pivotal connection between the main feed bar and the feed rocker is at a point above the fulcrum of the feed rocker and as the feed rocker is oscillated, a certain predetermined movement will be imparted to the main feed dog, the extent of which movement depends upon the throw of the feed rocker. The auxiliary feed bar through the link 28 is also pivotally connected to the feed rocker, but as shown in the drawings, at a point farther distant from the fulcrum 90 of the feed rocker than the pivotal connection for the main feed bar. During the oscillating movements of the feed rocker, therefore, the pivotal connection between said feed rocker and the link will move a greater 95 distance than the pivotal connection between the feed rocker and the main feed bar. This greater movement imparted to the pivotal connection between the link and the feed rocker likewise imparts a greater movement 100 to the auxiliary feed bar so that the auxiliary feed dog will be given a differential movement relative to the main feed dog and this differential movement may be adjusted by varying the position of the stud 29 in the 105 slot in the feed rocker. The feed dogs are moved up and down in unison by an eccentric 33 which is carried by the main shaft 18. Said eccentric bears against the hardened plate 21 and raises the two feed 110 bars which rest on said plate in unison. A bracket 34 is secured to the main feed bar by the screws 35 and extends underneath the eccentric 33, so as to positively lower the feed dogs from engagement with the material. Said bracket also extends at its rear 115 along the main feed bar, and forms a wearing plate for the projecting lug carried by the arm at the rear end of the auxiliary feed bar. 120

It will be seen from the above description that I have provided a feeding mechanism in which the two feed dogs are arranged one in advance of the other and wherein the mechanism for operating the feed dogs moves said feed dogs positively back and forth and up and down. It will be further noted that the above mechanism imparts an up and down movement to the feed dogs in 125 unison and that the forward feed dog may 130

be moved faster than the rearward feed dog, giving proper feeding movements to the feeding mechanism whereby the same is especially adapted for operating upon loose knit goods so that the same may be fed to the stitching mechanism without in any way stretching or distorting said knit goods. It will be obvious of course, that by my mechanism one feed dog may be moved faster than 10 the other for the purpose of ruffling or gathering the material.

Having thus particularly described my invention, what I claim as new and desire to secure by Letters Patent is:—

- 15 1. In a sewing machine, a feeding mechanism including in combination a main feed bar, a main feed dog carried thereby, a rocking frame fulcrumed on the bed of the machine, means for pivotally connecting said 20 main feed bar to said rocking frame at a point above said fulcrum, a second feed bar, a feed dog carried thereby and located in advance of said first named feed dog, means for raising and lowering said feed bars in 25 unison, and means for moving said second feed bar back and forth, including a link pivotally connected at one end to the rear end of said second named feed bar, and at its other end to a stud, said stud being adjustably secured in a substantially vertical slot formed in an upwardly projecting arm carried by said feed rocker.
2. A feeding mechanism for sewing machines including in combination, a main feed bar, a feed dog carried thereby, an auxiliary feed bar, a feed dog carried thereby, a laterally projecting hardened plate carried by the under face of one of said feed bars on which the other feed bar is adapted to rest 40 and slide, means for holding said sliding feed bar on said plate, means for moving said feed bars back and forth and for moving one feed bar relative to another, and means engaging said hardened plate for moving 45 said feed bars up and down in unison.
3. A feeding mechanism including in combination, a main feed bar, a feed dog carried thereby, an auxiliary feed bar, a feed dog carried thereby and located in advance of 50 the main feed dog, a laterally projecting hardened plate carried by the under face of one of said feed bars on which the other feed bar rests and slides, a second projecting plate carried by one of said feed bars and 55 extending over the other feed bar for holding it in engagement with said first named projecting plate, one of said plates having a projecting lip for forming an inclosed bearing in which the sliding feed bar moves,
- 60 means for moving said feed bars back and forth, giving one feed bar a sliding movement relative to the other, and means engaging said hardened projecting plate for moving said feed bars up and down in 65 unison.
4. A feeding mechanism for sewing machines including in combination a main feed bar, a feed dog carried thereby, an auxiliary feed bar, a feed dog carried thereby, a laterally projecting plate secured to one feed bar 70 on which the other feed bar is adapted to rest and slide, means for holding said last named feed bar in sliding engagement with said plate, one of said feed bars having a rearwardly projecting arm carrying a lug 75 extending underneath the other feed bar and slidably engaging the same for preventing the feed bars from tilting longitudinally relative to each other, means for moving said feed bars back and forth and for 80 sliding one feed bar relative to the other, and means for raising and lowering said feed bars in unison.
5. A feeding mechanism for sewing machines, including in combination a feed 85 rocker, means for oscillating said feed rocker, a main feed bar pivoted to said feed rocker, a laterally projecting plate carried by said main feed bar, an auxiliary feed bar resting and sliding on said projecting plate, a second plate for holding said auxiliary feed bar on said plate, a link pivoted at one end to the rear end of said auxiliary feed bar and adjustably connected at its other end to said feed rocker, means for raising 90 and lowering said feed bars in unison, a main feed dog carried by said main feed bar and an auxiliary feed dog carried by said auxiliary feed bar and located in advance of said main feed dog.
6. A feeding mechanism including in combination, a feed rocker, means for operating the same, a main feed bar pivotally connected to said feed rocker, a hardened plate secured to the under side of the main feed 100 bar and projecting laterally therefrom, a bracket carried by the under side of said feed bar, a cam located between said bracket and said hardened plate for raising and lowering said feed bar, a feed dog carried by said main feed bar, an auxiliary feed bar resting and sliding on said laterally projecting plate, a second plate carried by said main feed bar and engaging the upper face of the auxiliary feed bar for holding the 105 same on said first named plate, one of said plates having a laterally projecting lip for preventing the auxiliary feed bar from lateral movement, an auxiliary feed dog carried by said auxiliary feed bar and engaging the fabric in advance of the main feed dog, said auxiliary feed bar having a rearwardly projecting arm carrying a laterally projecting lug slidably engaging the under face of the main feed bar, a link pivoted to 110 said auxiliary feed bar at one end and having an adjustable pivotal connection with the feed rocker at its other end.
7. A feeding mechanism including in combination, a main feed bar, a feed dog, car- 115
- 120
- 125
- 130

ried thereby, an auxiliary feed bar, means for moving said feed bars back and forth and for giving said auxiliary feed bar a sliding movement relative to the main feed bar, an auxiliary feed dog carried by said auxiliary feed bar, means for moving said feed bar up and down in unison including a bracket having a part engaging the lower face of an eccentric, said bracket having a 10 rearwardly extending shank, said auxiliary feed dog having a rearwardly projecting arm carrying a lug which slidingly engages the shank of said bracket for preventing the auxiliary feed bar from tilting longitudinally relative to said main feed bar.

8. A feeding mechanism for sewing machines including in combination, a main feed bar, a feed dog carried thereby, an auxiliary feed bar extending to a point in advance of the needle, a feed dog, carried by said auxiliary feed bar, means for adjustably supporting said feed dog on the for-

ward end of said auxiliary feed bar, means for moving said auxiliary feed bar back and forth and up and down, said auxiliary feed bar having its under face adjacent the forward end thereof cut away so as to form a clearance for the stitch-forming elements coöperating with the needle below the work support.

9. A feeding mechanism for sewing machines including in combination, a main feed bar, a feed dog carried thereby, means for operating the main feed bar, an auxiliary feed dog, a support for the same located entirely at one side of the main feed bar, but with said auxiliary feed dog in line with the main feed dog.

In testimony whereof I affix my signature, in presence of two witnesses.

RUSSEL G. WOODWARD.
